Inventor,
H. B. Bigelow

United States Patent Office.

THOMAS BIGELOW, OF ELKHART, INDIANA.

Letters Patent No. 66,120, dated June 25, 1867.

IMPROVEMENT IN TINNERS' RULES.

The Schedule referred to in these Letters Patent and making part of the same.

TO ALL WHOM IT MAY CONCERN:

Be it known that I, THOMAS BIGELOW, of Elkhart, in the county of Elkhart, and State of Indiana, have invented certain new and useful Improvements in Tinners' Rules; and I do hereby declare that the following is a full and complete description thereof, reference being had to the accompanying drawings, making a part of this specification, in which—

Figure 1 is a view of the side of the rule for making pipes.

Figure 2 shows the side for making measures.

Figure 3 is a view of the edge of the rule.

Like letters of reference refer to like parts in the different views presented.

This rule is made in three sections A B C, each being one foot in length. These are connected to each other by a joint, D, fig. 3. Figs. 1 and 2 represent sections of the rule detached. E, fig. 1, is a scale of inches and fractions of an inch, the same as that on the common rule, and which may, in this case, be called a scale of circumference. F is also a scale of inches and fractions of an inch, and may be called a scale of diameter; and b, the joint scale.

This side of the rule is for the purpose of laying out the work for stove pipes, conductors, or pipe for any other purpose, and the application of which is as follows, commencing at the upper section of the rule: It is required to make a pipe one inch in diameter. Place a square on the line at the left-hand side of the figure 1 in the scale of diameters F. Now, whichever figures and fraction the square may indicate in the scale of circumference E, the same will be the circumference of the pipe. In this instance we find it to be $3\frac{1}{2}$ inches. In all tin pipes of less diameter than four inches $\frac{1}{8}$ of an inch is allowed for lapping in making. This, being added to the $3\frac{1}{2}$, gives $3\frac{1}{2}$ as the width to cut the work for one-inch pipe. The circumference of a two-inch pipe is $6\frac{1}{4}$ inches. Adding to this $\frac{1}{8}$ for lapping, as in the former case, we have $6\frac{5}{8}$ as the width to cut the work for a two-inch pipe. For sheet-iron pipe of 4 inches in diameter and upward one inch is allowed for the locking. As before, the circumference of a four-inch pipe is found in the second line of figures E, which is shown to be $12\frac{1}{2}$ inches. Adding to this one inch for lap or locking of the joint gives $13\frac{1}{2}$ inches as the width to cut the sheet. For a five-inch pipe the circumference is $15\frac{1}{4}$ inches. Adding one inch, as before, gives $16\frac{1}{4}$ as the width, and so on through the rule. It will be seen that this rule applies to pipes of fractional diameter, as $7\frac{1}{4}$, $7\frac{1}{2}$, $8\frac{1}{4}$, $8\frac{1}{2}$, &c.

In order that the several sections of pipe may fit together properly one end of the pipe is made smaller than the other. For ordinary stove pipe $\frac{1}{4}$ inch less in circumference is allowed for the small end. This difference in circumference will apply all the way through the rule. Take 11 inches in diameter, the circumference will be $34\frac{1}{2}$ inches. Add one inch for lock and we have $35\frac{1}{4}$ inches for the large end of the pipe. Allowing $\frac{1}{4}$ less for the small end gives $35\frac{1}{4}$ for the circumference, so that it will slip in the large end.

The scale H, fig. 2, is the opposite side of the rule, and is for liquid measure, the application of which is as follows: It is required to make a one-gallon measure, tapering from the bottom upwards. I, the first column of figures, gives the size of the measure; J gives the diameter of the top; K, that of the bottom, and L the height. By this it will be seen that the sheet of tin of which the measure is to be made is $8\frac{1}{2}$ inches in length. In order to find the circumference, apply the rule for making pipe, and we have $15\frac{1}{4}$ inches for the top, and $20\frac{1}{8}$ for the bottom, as the width to cut the work, allowing $\frac{1}{8}$ for locking, and so on through the scale.

The scale M is for dry measure, counting by bushels. The left-hand column of figures N gives the size of the measure; O, the diameter of the top; P, the diameter of the bottom, and Q the height; i. e., the work is to be cut $8\frac{1}{16}$ inches in length, the bottom $81\frac{1}{2}$, and the top $25\frac{1}{2}$, allowing, as before, $\frac{1}{8}$ for the locking.

The scale R is for making cans having a pitched top or a cone top. The left-hand column gives the size, D the diameter, the top and bottom being the same. H gives the height, and C the diameter of the cone; i. e., a one-gallon measure must be 6 inches in diameter, and $6\frac{1}{2}$ inches high. By applying the rule as before we find that the circumference is $18\frac{1}{2}$ inches, or the width to cut the work. C, in this scale, is "compass work," or the size to set the compasses to strike the circle to cut the cone top. After the piece is cut out the right size for the cone to fit the body of the can it makes the whole can of the right size to hold the amount indicated in the left-hand column. For the above-sized can set the compasses $6\frac{1}{2}$ inches, strike a circle, and then cut out a gore,

so as to leave it the same size as the body of the can. When formed it makes a cone about as high as the width, and so for each size given on the scale.

The scale S, for flat-top cans, gives the size in the left-hand column of figures, as in the former case. The circumference of the diameter is obtained in the same way as before, by applying the same rule as that for the pipe. In this scale we find that the diameter and height of the can are the same. To obtain this diameter apply the rule, and 21 $\frac{1}{4}$ inches is the circumference, or the width of the work, to make a one-gallon measure, as the scale specifies. The same process is pursued in the scale T, for dry measure or measuring grain.

What I claim as my invention, and desire to secure by Letters Patent, is—

The arrangement and construction of a rule comprising a system of scales, in the manner as herein set forth for the purpose specified.
